UNITED STATES PATENT OFFICE.

JOHN ALLEN HEANY, OF YORK, PENNSYLVANIA, ASSIGNOR TO THE TETER-HEANY DEVELOPING COMPANY, OF CHARLESTON, WEST VIRGINIA, A CORPORATION OF WEST VIRGINIA.

ELECTRIC-ARC LAMP.

SPECIFICATION forming part of Letters Patent No. 761,379, dated May 31, 1904.

Application filed December 4, 1903. Serial No. 183,703. (No model.)

To all whom it may concern:

Be it known that I, JOHN ALLEN HEANY, a citizen of the United States, residing at York, in the county of York and State of Pennsylvania, have invented certain new and useful Improvements in Electric-Arc Lamps, of which the following is a specification.

My invention has relation to an electric-arc lamp wherein electrodes are formed of materials which normally are non-arching; and in such general connection it relates to a means whereby in such a lamp the electrodes may be brought to and maintained in condition for arcing.

15 To those skilled in the art it is well known that certain substances—such as metallic oxides, metallic salts, &c.—are normally non-arching when used as the electrodes or terminals for the current. While such substances with 20 currents of high tension may perhaps when brought close together discharge the current in disrupted arcs or sparks, yet such disrupted arcing or sparking is not useful in the production of a light such as is emitted from the ordinary arc-lamp having carbon electrodes. I 25 have discovered how these normally non-arching materials may be brought to a condition wherein an arc of appreciable size and continuity can be formed and maintained between 30 electrodes composed of these materials, so that a light of greater luminosity and sharpness can be obtained at much less amperage than the amperage required in either the ordinary incandescent or arc lamp.

35 The principal object of my present invention is to provide an electric-arc lamp having electrodes connected directly with the terminals of the current and normally non-arching combined with means whereby an arc may be 40 produced and maintained between the electrodes under a low amperage.

The nature and scope of my invention will be more fully understood from the following description, taken in connection with the accompanying drawings, forming part hereof, in which—

Figure 1 is a sectional view illustrating diagrammatically an arc-lamp embodying main

features of my invention, and Fig. 2 is a front elevational view of a modified form of electrodes.

Referring to Fig. 1 of the drawings, *a* represents a hollow plug of dielectric material, surrounded by a screw-cap *b*, of metal, having a downwardly-projecting flange *b'*, into which a globe *d* is fitted. Within the hollow of the plug *a* is secured a carbon or graphite resistance *e*, connected by a metallic plug *e'* with one terminal of the circuit. The screw-cap *b* is connected with the other terminal of the circuit. The electrodes *f*, *f'* of the lamp are respectively connected with the resistance *e* by a divided wire *g*, the ends of which are connected by a thermostat *h* and a continuous wire *i*, depending from the screw-cap *b*. So far as described the parts and their arrangement are comparatively unimportant and embody merely one of many forms of lamps in which my present invention may be embodied or carried out. In Fig. 1 the electrodes *f*, *f'* are spherical, or substantially so, in shape. In Fig. 2 the electrodes *f*', *f* are pencils of the materials. One or both of each of the electrodes *f*, *f'* or *f*', *f*' is or are formed of a material normally non-arching at ordinary temperatures—such, for instance, as the metallic oxides or salts of metals, such as cerium, thorium, calcium, magnesium, yttrium, &c. Where these oxides or salts are sufficiently coherent to be molded or formed into the shape required and to maintain the same under the influence of high heat, they may be used alone; otherwise a binding agent such as a borate, carbonate, phosphate, sulfate, or even boracic acid should be used. When the electrodes are formed of such non-arching materials, no appreciable continuous or luminous arc will be produced at ordinary temperatures of the electrodes with a current of even a high or relatively high tension. When, however, the electrodes of non-arching materials are first heated to redness or substantially to incandescence, an arc of appreciable size and continuity will be formed and maintained between the electrodes when the tension of the current is relatively low and the amperage much less than is required in

the ordinary incandescent or filament lamp. Not only is such a continuous arc formed or maintained, but the luminosity and sharpness of the light is materially greater than that which the incandescent lamp gives under greater consumption of current. One means of initially heating the electrodes $f f'$ or $f' f''$ may be a spirit-lamp or Bunsen burner m , as illustrated in Fig. 2. Another which is not extraneous to the lamp, and therefore preferable, is to incorporate in the electrodes a highly-conductive material—such, for instance, as platinum, gold, iridium, &c.—which, as is well known, are good conductors within ordinary temperatures. The effect of combining or incorporating such a good conductor with the non-arching material or materials is to render such material or materials a partial conductor or conductor of high resistance. When the electrodes $f f'$ or $f' f''$ touch, as illustrated in the drawings, the passage of the current through the electrodes $f f'$ and $f' f''$ of high resistance serves almost instantaneously to heat the electrodes to redness or incandescence. By including a resistance e , of graphite or similar material, in the circuit the flow of current to the electrodes will be regulated inversely to the distance the electrodes are separated from each other to form the arc. The inclusion of a thermostat h or equivalent arc-adjusting means in the circuit renders the regulation of the size of the arc automatic.

Having thus described the nature and object of my invention, what I claim, broadly, as new, and desire to secure by Letters Patent, is—

1. In an electric-arc lamp, an electrode formed of normally non-arching material, in combination with an electric circuit, one terminal of which is connected directly with said electrode, and means for forming and maintaining an arc upon said electrode during the passage of the current therethrough.

2. In an electric-arc lamp, an electrode forming a terminal for the current and consisting of material non-arching at normal temperatures, combined with means for heating said electrode to a temperature at which an arc

may be formed and maintained upon said electrode during the passage of the current therethrough.

3. In an electric-arc lamp, two electrodes each formed of normally non-arching material and each forming a terminal for the current, combined with means for forming and maintaining an arc between said electrodes during the passage of current through said electrodes.

4. In an electric-arc lamp, two electrodes each formed of material non-arching at normal temperatures and each forming a terminal for the current, combined with means for heating said electrodes to a temperature at which an arc may be formed and maintained between said electrodes during the passage of the current therethrough.

5. In an electric-arc lamp, an electrode forming a terminal for the current and consisting of an oxid or oxides of the rare metals, combined with means for heating said electrode, whereby an arc may be formed and maintained thereon during the passage of the current therethrough.

6. In an electric-arc lamp, an electrode forming a terminal for the current and consisting of a material non-arching at normal temperatures, combined with a good conductor arranged to form with the non-arching material an electrode of high resistance at normal temperatures, in combination with means for passing the current through said electrode to heat the same to a temperature at which an arc may be formed and maintained upon said electrode during the passage of current therethrough.

7. In an electric-arc lamp, an electrode formed of a metallic oxid, and a binder consisting of a borate or its equivalent, combined with means for heating the electrode to form and maintain an arc upon the electrode.

In testimony whereof I have hereunto set my signature in the presence of two subscribing witnesses.

JOHN ALLEN HEANY.
